PERCIVAL NESBIT WILLOUGHBY, OF BROADSTONE, DORSET, ENGLAND

FLYING MACHINE

Application filed October 29, 1931, Serial No. 571,802, and in Great Britain November 3, 1930.

This invention relates to flying machines and in particular to the shape and formation of the supporting and stabilizing surfaces and it has for its objects a construction which

5 will be more compact for a given weight carried and landing speed; which can assume large angles of incidence in flight without loss of lift and which will remain stable and controllable at large angles of incidence 10 responding to low speeds.

In flying machines as at present constructed having a wing of large aspect ratio, if the machine rolls while flying at a large angle of incidence auto-rotation may set in which may 15 develop into a spiral dive or spin.

According to the present invention it is proposed to overcome this tendency by constructing the machine with a main plane of high aspect ratio and a tail plane of usual 20 aspect ratio integrally connected together by side wings of small aspect ratio, the main plane extending beyond the side wings to an extent approximately equal to half the maximum width of the aperture between the side 25 wings, all surfaces being suitably cambered for good lift, low drag and stability so that the lift of the whole surface will continue to increase at much larger angles of incidence than is possible with wings as at present constructed without the provision of special devices.

According to one embodiment of the invention the total supporting surface will approximate in shape a triangle, having a front wing 35 of considerable aspect ratio joined to a tail plane by means of side wings of small aspect ratio; for example, of less width in the direction of the span of the machine than the length of said side wings.

40 It is further proposed, according to this invention, to provide supplementary means of aerodynamical control, particularly lateral control, at large angles of incidence corresponding to low speeds, and to this end it is proposed to provide an aeroplane of the type herein described with surfaces of small or fractional aspect ratio and to furnish suitable means for manipulating said surfaces so 45 that they can continue to function as a means

of control even when they or the machine to which they are fitted reach large angles of incidence without the use of slots or other supplementary devices.

In the accompanying drawings which illustrate, mainly diagrammatically, an embodiment of this invention as applied to a monoplane by way of example:—

Figure 1 is a front elevation;

Figure 2 is a plan, and,

Figure 3 is a side elevation;

Figure 4 is a plan of one-half of the lifting surface, on an enlarged scale, to illustrate the cambers at various sections of the lifting and stabilizing surfaces;

Figure 5 is a side elevation of Figure 4;

Figure 6 is a side elevation of the control mechanism;

Figure 7 is a section on line $w-w$ of Figure 6;

Figure 8 is a section on line $x-x$ of Figure 6, and,

Figure 9 is a perspective view of the supporting and stabilizing surfaces and the aerofoils for lateral control, diagrammatically illustrating an arrangement of the cables for controlling the moving parts of such surfaces and aerofoils.

Referring to the drawings, 1 is the main or front plane, the incidence and camber of which may be constant or graded as shown and may be the same or differ from that of the side wings, 2 but in any case sufficient effective longitudinal dihedral must be provided on the machine to preserve longitudinal stability. In order to provide for a degree of lateral control and also to improve efficiency the front plane 1 is extended in the form of wing-tips 3 beyond the junction of the side planes 2 therewith and, if desired, 40 ailerons 4 may be hinged thereto in known manner or the wing-tips 3 may be movable as a whole on a transverse axis, that is, on an axis parallel or approximately parallel with the leading edge of the front plane. The front plane 1 between the longitudinal axis and the wing-tip may be so graded in camber as to form a smooth juncture at the points where the side planes 2 sweep into said front plane and a similar grading of camber is also 45 50 55 60 65 70 75 80 85 90 95 100

provided for at the point where the side planes sweep into the tail plane 5, as shown by the camber sections in Figure 4, and the junctures of the side planes 2 with the front plane or with each other at the rear or with the tail plane are preferably radiused as shown at 6 and 7 respectively, Figures 2 and 4.

10 The longitudinal and transverse sections of the side wings are preferably such that what is commonly termed the centre of pressure moves in a stabilizing direction on variation of incidence and yaw and such movement may be aided by a transverse dihedral.

15 The slope back of the side wings together with their transverse sections are so arranged as to right the machine following a yaw due to rolling, and the junction of the side wings with the tail plane or with themselves may be 20 arranged to assist in this action.

25 Suitable provision is made for the attachment to the tail plane 5 of elevators 8, rudder 9 and fins 10 of suitable form. The body of the machine is indicated at 11, the engines at 12 with under-carriages 13 supported by struts in any desired manner.

30 Referring to Figures 4 and 5, the broken lines represent a horizontal or datum surface and where the base line of a particular camber section coincides with said datum line as at the points 13 it indicates that the under-surface of the plane at that point is touching the datum surface and where such base line is located to one side of the datum line as at the 35 points 14 it indicates that the under-surface of the plane at those points is raised above the datum surface to give the desired camber and longitudinal or lateral dihedral.

35 The supplementary means of aerodynamical control as stated above consists in the provision of surfaces of small or fractional aspect ratio and comprise the aerofoils 15, 15 α formed separately from the wings and located preferably, as shown in Figures 1, 2 40 and 9, at a considerable distance from the longitudinal axis of the machine towards or beyond each wing-tip. The aerofoils 15, 15 α may be located above or as shown below the level of the wings and their upper and lower 45 surfaces may each or both be cambered or said surfaces may be sensibly flat. The aerofoils are pivotally mounted on axes 16 (Figure 9) carried by a suitable framework 17 secured to the wings, said axes being disposed 50 approximately at right angles to the direction of lift and to the longitudinal axis of the machine so that when not in use said aerofoils lie with their surfaces approximately horizontal and so that their incidence can be 55 increased over a wide range either positively or negatively as desired under the control of the pilot.

60 The aerofoils are preferably so connected to the control lever in the cockpit that the incidence of one is increased and that of the 65

other decreased to an equivalent amount by one motion of the control lever or wheel in the usual manner, and the pivotal axis is so disposed relatively to the chord of either aerofoil as to provide, from the average leverage of the centre of pressure of the forces brought into play by such movement, a suitable resistance at the control lever or wheel.

65 As shown on the drawings, small aspect ratio aerofoils as above described may, if desired, be used in combination with wing ailerons of the usual type. According to one embodiment of this combination, the ordinary wing ailerons may be used alone in the usual manner during flight at high and moderate speeds, but may be arranged to be thrown out of use and the control taken up by the small aspect ratio aerofoils when low speeds or large angles are reached. In this particular embodiment or when small aspect 80 ratio aerofoils are used without the ordinary wing ailerons, the small aspect ratio aerofoils may be set at or near the floating angle of incidence of approximately no lift whatever the speed while the machine is in lateral trim, 85 so that full reserve for change of incidence for purposes of control is always retained.

90 An example of control operating mechanism will now be described with reference to Figures 6 to 9 of the accompanying drawings. A type of lateral control operating mechanism of known form consisting of a control wheel 18 is provided with supplementary pulleys 19, 20, 21, 22 and 23, so that the control may be by (a) ordinary ailerons 95 alone; (b) ordinary ailerons and small aspect ratio aerofoils combined and (c) small aspect ratio aerofoils alone. Additional pulleys or other gear are also provided for adjustment of the incidence of both of the 100 small aspect ratio aerofoils together to about their angle of no lift.

105 To carry this into effect the usual control wheel 18 is secured on the end of a spindle 24 mounted in a bearing 25 provided at the upper end of the control stick 26 and at the forward end of this spindle are secured two pulleys 19, 20 to which are connected the usual control wires 27, 28 attached to the horns 29 and 30 on the ordinary ailerons 4 110 by means of which they are operated by a simple rotative movement of the wheel 18 in either direction. Three further pulleys 21, 22 and 23 are mounted, adjacent the pulley 20, and the boss 31 of each of said pulleys 115 is furnished with grooves or the like 32 to enable same to be engaged by splines 33 provided on the forward end of a sleeve 34 which fits over and slides longitudinally on and around the spindle 24, said splines being so arranged that any two adjacent pulleys may be locked together as desired so that the low aspect ratio aerofoils 15, 15 α can be operated 120 to move simultaneously in similar or differential directions. The bosses of the pulleys 125 130

21, 23 are formed so that when the splined sleeve 34 is out of engagement therewith said pulleys will rotate freely on the spindle 24 and sleeve 34 respectively; the pulley 22 is at all times in engagement with the splines on the sleeve 34. To the rear end of the sleeve 34 is secured a bar, wheel or other device 35 the ends or periphery 36 of which are arranged to extend beyond the periphery of the control wheel 18, the arrangement being such that the device 35 may be actuated independently of or simultaneously with the control wheel 18. The normal position of the sleeve 34 is preferably, though not necessarily, as shown, so arranged that the two foremost pulleys 21, 22 are locked together by the splined sleeve 34 and to this end a collar 37 is secured to the sleeve 34 adjacent the rear face of the pulley 23, a second collar 38 being slidably mounted on the sleeve with a coil spring 39 of suitable strength located between the two collars, the loose collar 38 being arranged to bear against the bearing 25 in which the sleeve 34 is slidably mounted.

Suitable means are provided for preventing any endwise movement of the spindle 24 apart from the control stick 26, and such means may consist of a bar 40 secured at one end to the control stick, the other being shaped to enable it to engage with the forward end of the spindle 24 as shown. The bosses of the several pulleys are arranged to bear against each other or suitably formed thrust bearings may be interposed between each boss. Endwise movement of said pulleys may be prevented by the provision of an arm 40a secured to the control stick 26 or to the arm 40 as shown.

The method of connecting up the various control wires for the aerofoils 15, 15a will now be described with particular reference to Figure 9. The aerofoil 15a is controlled by the single wire 41 which is secured to the pulley 22 at 42, the free ends being secured fore and aft of the aerofoil. The aerofoil 15 is controlled by the single wire 43 secured to the pulley 21 at 44, the free ends being secured fore and aft of the aerofoil. By these connections and pulleys it is possible to impart a differential movement only to the aerofoils. As it is preferable also to be in a position to impart a similar movement to the two aerofoils the pulley 23 is provided and the control wire 45 secured thereto at 46 is crossed, as shown in Figures 8 and 9, and connected to the control wire 43 at the points 47.

The method or operation of the controls is as follows:—The ordinary ailerons 4 are controlled by the wheel 18 acting on the pulleys 19 and 20 as above described. The aerofoils 15 and 15a are actuated differentially by locking together the pulleys 21 and 22.

As it will be necessary in certain circum-

stances to adjust the angle of incidence of the aerofoils simultaneously thereby necessitating said aerofoils being first placed in the neutral position, an indicating arm may be provided on the sleeve 34 arranged to contact with means comprising, for example, a dial on the dash board. To effect this movement the pilot will first turn the bar and thereby the pulleys 21 and 22 normally locked together until the indicator arm points to the neutral position, when at this position the bar 35 is drawn rearwardly towards the wheel 18 against the action of the spring 39 so as to withdraw the splines 33 from engagement with the grooves in the pulley 21 and at the same time lock together the pulleys 22 and 23. If the bar 35 and thereby sleeve 34 is now turned to a point on the dial indicated by the arm on the sleeve, the aerofoils will be moved simultaneously in the same direction to the requisite extent and when this is set the sleeve 34 is allowed to return under the influence of the spring to its normal position so that the aerofoils may be adjusted differentially.

If said aerofoils after setting are not required for differential use suitable means are provided for locking the sleeve against rotation in the neutral position as set. Alternatively said aerofoils may be required for differential use alone in which case the suitable means are provided for locking the spindle against rotation in an arranged neutral position.

The rudder and fins may, if desired, be duplicated and the rudder and elevators are actuated and controlled in the usual manner.

It will be understood that the low aspect ratio aerofoils may, if desired, be used as air-brakes for which purpose their incidence when not differentially deflected may be reset, as above described, to a considerable positive or negative angle thereby considerably increasing the drag, after which they may, if desired, be operated differentially.

It will also be understood that the invention is not limited to the particular method of operation or control as above described as various of the selective adjustments above described may be dispensed with.

The plan form of the low aspect ratio aerofoils may, in general, approximate to the rectangular shape, but they may, if desired, be of elliptic or other desired form, and as regards their aspect ratio, the span may be less or somewhat greater than the mean chord. The upper and lower surfaces may be cambered longitudinally, or transversely or both for increasing efficiency. The aerofoils may be attached to the wings by double tripod erections and pivoted as above described at their sides, or they may be pivoted within their spans.

It will further be understood that the invention is not limited to the approximately

triangular form above described as it may be found practical to increase the distance between the rearward ends of the low aspect ratio planes, so that they may approximate with the main and tail planes, a rectangular or trapezium form.

The invention may be applied to aeroplanes, seaplanes or flying-boats of the monoplane or multiplane type.

10 When the low aspect ratio aerofoils are used in connection with sea-planes or flying-boats having the supporting and stabilizing surfaces formed as above described, the undersides of each of said aerofoils may be furnished with a keel or step or be otherwise shaped to make same suitable to act as floats.

What I claim is:—

1. A flying machine comprising a body, cambered main and tail planes, rudders and elevators for supporting said body, ailerons hinged to said main planes, a control wheel in said body, means connecting said wheel with said ailerons in combination with fixed cambered supporting surfaces of small aspect ratio connecting the main planes with the tail planes, supplementary means of aerodynamical lateral control comprising aerofoils of small aspect ratio, located at a distance from the longitudinal axis on each side of the machine and means connecting said aerofoils with the control wheel so that the control of the machine may be effected by ordinary ailerons alone, by ordinary ailerons and small aspect ratio aerofoils combined and by small aspect ratio aerofoils alone.

2. A flying machine comprising a body having an engine mounted therein, main and tail planes, rudders and elevators for supporting said body, ailerons hinged to said main planes, a control wheel in said body, means connecting said wheel with said ailerons in combination with fixed supporting surfaces of small aspect ratio connecting the main planes with the tail planes, so that the total fixed supporting surfaces approximate a triangle, supplementary means of aerodynamical lateral control comprising aerofoils of small aspect ratio, located at a distance from the longitudinal axis of the machine towards the wing tips and means connecting said aerofoils with the control wheel so that the control of the machine may be effected by ordinary ailerons alone, by ailerons and small aspect ratio aerofoils combined and by small aspect ratio aerofoils alone.

3. A flying machine comprising a body, cambered main and tail planes, rudders and elevators for supporting said body, ailerons hinged to said main planes, a control wheel in said body, means connecting said wheel with said ailerons combined with fixed cambered supporting surfaces of small aspect ratio connecting the main planes with the tail planes, supplementary means of aerodynamical lateral control comprising aerofoils of small as-

pect ratio located at a distance from the longitudinal axis on each side of the machine towards the wing tips, aerofoils and means connecting said aerofoils with the ailerons and control wheel so that the angle of incidence of the aerofoils and ailerons may be adjusted simultaneously.

4. A flying machine comprising a body having an engine mounted therein, main and tail planes, rudders and elevators for supporting said body, ailerons hinged to said main planes, a control wheel in said body, means connecting said wheel with said ailerons, fixed supporting surfaces of small aspect ratio connecting the main planes with the tail planes, so that the total fixed supporting surfaces approximate a triangle, supplementary means of aerodynamical lateral control comprising aerofoils of small aspect ratio, the span of which is less than the mean chord, located at a distance from the longitudinal axis of the machine towards the wing tips, means connecting said aerofoils with the ailerons hinged to the main planes and means connecting said aerofoils with the control wheel so that the angle of incidence of the aerofoils and ailerons may be adjusted simultaneously.

5. A flying machine comprising a body having an engine mounted therein, fixed and movable surfaces of normal aspect ratio for supporting said body, a control wheel in said body, means connecting said control wheel with certain of the movable supporting surfaces combined with fixed supporting surfaces of small aspect ratio connecting the fixed front supporting surfaces with the fixed tail supporting surfaces so that the total fixed supporting surfaces approximate a triangle, supplementary movable means of aerodynamical lateral control comprising surfaces of small aspect ratio located at a distance from the longitudinal axis of the machine and means connecting said surfaces with the control wheel so as to vary the angle of incidence of said surfaces.

6. A flying machine comprising a body, fixed and movable surfaces of normal aspect ratio for supporting said body, a control wheel in said body, means connecting said control wheel with certain of the movable supporting surfaces combined with fixed supporting surfaces of small aspect ratio connecting the fixed front supporting surfaces with the fixed tail supporting surfaces, supplementary movable means of aerodynamical lateral control located at a distance from the longitudinal axis on each side of the machine and means connecting said surfaces with the control wheel so as to enable the angle of incidence of one of said surfaces to be increased and that of the other decreased to an equivalent amount.

7. A flying machine comprising a body having an engine mounted therein, fixed and

movable surfaces of normal aspect ratio for supporting said body, a control wheel in said body, means connecting said control wheel with certain of the movable supporting surfaces combined with fixed supporting surfaces of small aspect ratio connecting the fixed front supporting surfaces with the fixed tail supporting surfaces so that the total fixed supporting surfaces approximate a triangle, supplementary movable means of aerodynamical lateral control comprising aerofoils of small aspect ratio located at a distance from the longitudinal axis on each side of the machine beyond each wing-tip and means connecting said surfaces with the control wheel so as to vary the angle of incidence of said aerofoils simultaneously in the same direction.

8. In a heavier than air flying machine the combination of main planes of usual aspect ratio with lifting surfaces of small aspect ratio comprising a cambered front plane of considerable aspect ratio joined to a tail plane by means of cambered side planes of small aspect ratio, supplementary means of aerodynamical lateral control at large angles of incidence comprising surfaces of fractional aspect ratio located at a distance from the longitudinal axis on each side of the machine and means for controlling said low aspect ratio aerofoils so that the angle of incidence may be varied as desired.

9. In a heavier than air flying machine the combination of main planes of usual aspect ratio with lifting surfaces of small aspect ratio arranged to approximate in shape a triangle, said surfaces comprising a cambered front plane of considerable aspect ratio joined to a tail plane by means of cambered side planes of small aspect ratio, wing tips on said front plane extending beyond the junction of the side planes therewith and movable on a transversely disposed axis, supplementary means of aerodynamical lateral control at large angles of incidence comprising a low aspect ratio aerofoil located at a distance from the longitudinal axis on each side of the machine towards the wing tips and means for controlling said low aspect ratio aerofoils so that the angle of incidence may be varied as desired.

10. In a heavier than air flying machine the combination of main planes of usual aspect ratio with lifting surfaces of small aspect ratio, the total supporting surface approximating in shape a triangle comprising a cambered front plane of considerable aspect ratio joined to a tail plane by means of cambered side planes of small aspect ratio, wing tips on said front plane extending beyond the junction of the side planes therewith and movable on a transversely disposed axis, supplementary means of aerodynamical lateral control at large angles of incidence comprising surfaces of fractional aspect ratio lo-

cated at a distance from the longitudinal axis on each side of the machine towards the wing tips and below the level of the front plane, and means for controlling said low aspect ratio aerofoils so that the angle of incidence may be varied as desired.

11. A flying machine comprising a body having an engine mounted therein, main and tail planes, rudders and elevators for supporting said body, ailerons hinged to said main planes, fixed supporting surfaces of small aspect ratio connecting the main planes with the tail planes, supplementary means of aerodynamical lateral control comprising aerofoils of small aspect ratio, a control mechanism in said body comprising a control shaft, a wheel secured on said shaft, a plurality of pulleys mounted on said shaft, means connecting certain of said pulleys to the ailerons and aerofoils and means for locking certain of said pulleys together so that the control of the machine may be by ordinary ailerons alone, by ailerons and small aspect ratio aerofoils combined and by small aspect ratio aerofoils alone.

12. A flying machine comprising a body having an engine mounted therein, main and tail planes, rudders and elevators for supporting said body, ailerons hinged to said main planes, fixed supporting surfaces of small aspect ratio connecting the main planes with the tail planes, so that the total fixed supporting surfaces approximate a triangle, supplementary means of aerodynamical lateral control comprising aerofoils of small aspect ratio, the span of which is less than the mean chord, located at a distance from the longitudinal axis of the machine towards the wing tips, a control mechanism in said body, comprising a control shaft, a wheel mounted on one end of said shaft, a pulley secured on the other end of said shaft and means connecting said pulley with the ailerons on the main plane, further pulleys freely mounted on said control shaft and means connecting same with the low aspect ratio aerofoils, and clutch mechanism slidably arranged on the control shaft for locking certain of the pulleys together so that the control of the machine may be by ordinary ailerons alone, by ordinary ailerons and small aspect ratio aerofoils combined and by small aspect ratio aerofoils alone.

13. A flying machine comprising a body having an engine mounted therein, fixed and movable surfaces of normal aspect ratio for supporting said body, a control mechanism in said body, means connecting said mechanism with the movable supporting surfaces, fixed supporting surfaces of small aspect ratio connecting the fixed front supporting surfaces with the fixed tail supporting surfaces so that the total fixed supporting surfaces approximate a triangle, supplementary movable means of aerodynamical lateral control

comprising aerofoils of small aspect ratio located at a distance from the longitudinal axis of the machine, means such as a keel provided on the undersides of said aerofoils whereby they are rendered suitable to act as floats, and means connecting said aerofoils with the control mechanism so as to control the angle of incidence of said surfaces.

14. A flying machine having a main plane of high aspect ratio and a tail plane of usual aspect ratio integrally connected together by side wings of small aspect ratio, the whole being continuously cambered, the main plane extending beyond the side wings to an extent approximately equal to half the maximum width of the aperture between the side wings.
